(57) **CLAIM**

The ornamental design for a floor cleaning pad, as shown and described.

DESCRIPTION

FIG. 1 is a perspective view of a floor cleaning pad;

FIG. 2 is a top view thereof, the bottom view being a mirror image of the top view;

FIG. 3 is a right side view thereof, the left side view being a mirror image of the right side view;

FIG. 4 is a front view thereof; and,

FIG. 5 is a rear view thereof.

The broken lines in the drawings are shown for illustrative purposes only and form no part of the claimed design. In addition, the surface shading illustrated in the drawings is provided merely to highlight the contour of design; it is not intended to be illustrative of texture or gloss.
